FIG. 1 is a perspective view from the front of my new design for a GPS hood.

FIG. 2 is a perspective view from the rear of my new design for a GPS hood.

FIG. 3 is a front elevational view of the device shown in FIG. 1.

FIG. 4 is a rear elevational view of the device shown in FIG. 1.

FIG. 5 is a bottom plan view of the device shown in FIG. 1.

FIG. 6 is a top plan view of the device shown in FIG. 1.

FIG. 7 is a left side elevational view of the device shown in FIG. 1; and,

FIG. 8 is a right side elevational view of the device shown in FIG. 1.
